UNITED STATES PATENT OFFICE.

EDMUND W. ZEH, OF NEWARK, NEW JERSEY.

CLUTCH-OPERATING MECHANISM FOR POWER PRESSES.

Application filed August 29, 1925. Serial No. 53,239.

This invention relates to that class of power presses in which a clutch throw-out is employed for stopping the press upon the completion of a stroke, and an operating 5 rod provided for holding said throw-out in idle position when the press is desired to deliver repeated blows or work continuously.

The objects of this invention are to enable the operating rod to be either permanently 10 connected to the clutch throw-out for repeat or continuous work or releasably connected to said throw-out in order to necessitate a separate manual operation of it for each stroke of the press; to thus enable the press 15 to be operated continuously by a workman when extreme care is not required, and to be operated by a separate actuation of the throw-out for each stroke when great care is necessary; to secure a new and simple 20 construction for this purpose, and to obtain other advantages and results as may be brought out by the following description.

Referring to the accompanying drawings, in which like characters of reference indicate 25 the same parts in the several views,

Figure 1 is a side elevation of a press embodying my invention, showing the parts in position for repeated strokes or continuous action of the press upon depression 30 of the operating rod, with the driving wheel removed for greater clearness; Figure 2 is a similar view on a larger scale with the parts in position for the press to automatically stop at the completion of 35 a single stroke upon depression of the operating rod;

Figure 3 is a section on line 3—3 of Fig. 2, looking in the direction indicated by the arrows;

Figures 4 and 5 are views showing the engagement of the operating rod with the throw-out for intermittent and for continuous action of the press, respectively;

Figure 6 is a section on line 6—6 of Fig. 45 5, looking in the direction indicated by the arrows, and

Figure 7 is a detail view partly in section of a certain arm for positioning the parts for repeated strokes or for single strokes.

In the specific embodiment of the invention shown in said drawings, 1 indicates the frame of a press having a bed 2, guard 3 and head 4 adapted to be reciprocated by a pitman 5 upon the eccentric (not shown) of a shaft 6 journaled in the upper part of said frame 1. A driving wheel (not shown) is

loose upon said shaft 6 and adjacent to it is a clutch member 7 fast upon the shaft and carrying a clutch pin 8 normally projected by a spring (not shown) to be engaged by the driving wheel. Said clutch member 7 is annularly slotted, and a throw-out 9 pivoted to swing in the plane of said slot has a free end lying in said slot to engage the clutch pin 8 and retract it from the driving wheel. All said parts as described above are old and well-known in the art so that they need no further description or illustration here, their operation being that when the throw-out 9 is swung out of engagement with the clutch pin, said clutch pin is automatically projected and engaged by the driving wheel to carry the shaft around with it, but after the throw-out has been released it automatically returns, as by a spring, to again engage the clutch pin at the end of a complete rotation and stop the head 4 in raised position. If the throw-out has not been released the press will operate repeatedly or continuously, and sometimes when it is desired to stop at the end of a single stroke the operator does not act promptly enough to accomplish it. It is the purpose of the present invention to provide a construction additional to that above described which will ensure 70 that when the press is intended to deliver single strokes it will automatically stop at the end of a stroke and not start again except upon a manual act by the operator, and yet nevertheless it can be set so as to make 75 repeated strokes or operate continuously upon a manual act by the operator

In carrying out my invention I mount the throw-out 9 at its outer end upon a pin or stud 10 projecting from a boss 11 of the frame 1, see Figure 3, said boss having only portions of itself machined for the throw-out to rest upon, two of which are indicated by reference numeral 12. Also, upon the pin or stud 10 is pivoted a casting 13 having 80 a hub portion slotted as at 14 to partly receive the throw-out and secured thereto as by screws 15; arms 16, 17 extend upward and downward, respectively, from the throw-out, bending also inward toward the frame 1, 85 and provide at their ends each a tapped seat for a stop screw 18 adapted to engage the boss 11 and thus limit swinging of the throw-out. The bottom stop screw has a lock nut 19, and obviously by adjustment of said 90 screws movement of the throw-out can be limited so as not to wear against the bottom

of the annular groove in the clutch member 7, on one hand, and not to swing any further outwardly of said groove than to clear the clutch pin 8.

5 The said casting 13 has a further upwardly and inwardly extending arm 20 which at its end slidably receives a rod 21 which at its other end is pivoted to the frame 1 at a point nearer the clutch member 7 so that an expansion spring 22 upon said rod between its pivoted end and the arm 20 normally swings said arm, and therefore the throw-out 9 to hold the same in position to disengage the clutch pin 8, the lower stop screw 18 engaging the under edge of the boss 11, all as shown in Figure 2.

From a treadle 23 at the lower part of the machine a connecting rod 24 extends upward to an arm 25 on a shaft 26 mounted in the frame 1 a little above the bed 2, said shaft carrying the guard 3 so that the same is operated by the parts just described. From said arm 25 a connecting bar 27 extends upward past the throw-out 9, preferably between it and the frame 1, and is connected at its upper end by a helical spring 28 to the end of an arm 29 pivoted upon the frame 1, as at 30. This arm 29 is adapted to occupy either the position shown in Figure 1 or the position shown in Figure 2, for reasons herein-after explained, the spring 28 in either case drawing the extremity of the connecting bar 27 toward the free end of the arm 29, and preferably the two positions of said arm 29 are determined by some such suitable means as the following, see Figures 7 and 2. The hub 31 of the said arm 29 is spaced a little from the frame 1, and a spring 32 placed around said hub to normally force the arm outward, the outer face of the hub being provided with grooves 33, 34 which are adapted one to receive a radial pin 35 on the pivot stud 30 in one position of the arm and the other to receive said radial pin in the other position of the arm. Obviously, by pressing the arm toward the frame it can readily be disengaged from said pin to turn it from one position to the other, and yet it will not inadvertently escape from either position.

50 Where the connecting bar 27 passes the throw-out 9 it is preferably narrowed in an edgewise direction, from both edges to form shoulders 36, 37 and said narrowed portion preferably lies in a groove 38 in the throw-out 9, which groove is sufficiently wide so that only one of said shoulders will hook onto a side wall of the groove at the top of said throw-out at one time, the other shoulder falling enough short of the opposite edge wall of the groove so that if the first one is disengaged the bar 27 will slide in the groove 38. This is accomplished in the construction shown by making the groove 38 wider than the shouldered portion of

the connecting bar 27, but it is within the scope of my invention to accomplish it in any other suitable way. When the arm 29 of the top of the frame is thrown into the position shown in Figure 2, the shoulder 36 70 overlies the wall of the slot 38 next the free end of the throw-out, said connecting bar being elevated by the treadle spring 39 so as to hold its stop 40 against the lower edge of the throw-out and said throw-out being 75 further elevated into position to engage the clutch pin 8 by the spring 22 pushing against the arm 20 until the lower stop screw 18 engages the underside of the boss 11. With the parts in this position, if the operator depresses the treadle the clutch pin 8 will spring into engagement with the fly wheel and the head 4 of the press begin to make a stroke; as the clutch member 7 revolves, however, the pin 8 strikes the edge 85 of the connecting bar 27, as clearly shown in Figure 2, and swings it to the right hand as shown, against the pull of the spring 28, sufficiently to disengage the throw-out 9 which at once returns to normal position to 90 engage the clutch pin 8 as it comes around upon the completion of a stroke and stop the press. It will be noted that this stopping at the end of a single stroke occurs automatically whether or not the operator removes his foot from the treadle, and thus 95 there is no possibility of a second stroke such as might damage the work or injure the operator.

On the other hand, if the arm 29 is thrown 100 into its other position, as shown in Figure 1, the shoulder 37 overlies the throw-out 9 at the edge of its groove 38 away from the free end of the throw-out, and upon depression of the treadle 23 to disengage the 105 throw-out 9, said connecting bar 27 lies far enough away from the shaft 6 so that the clutch pin 8 as it comes around clears said bar and the throw-out 9 remains retracted or lowered. The press will therefore make 110 repeated strokes or operate continuously as long as the operator keeps the treadle 23 depressed, and will stop only when he takes his foot off. By my improved construction, therefore, a press can be operated in either 115 way, as may be desired to suit different conditions, and the means for enabling this are very simple, efficient and not likely to get out of order. In both positions of the arm 29 the spring 28 holds the connecting 120 bar 27 in position to engage the throw-out 9 as desired, and it is very quickly and easily shifted from one position to the other to change from one mode of operation of the 125 press to the other.

Obviously, various structural modifications may be made by those skilled in the art in carrying out my invention, without departing from the spirit and scope thereof, and therefore I do not desire to be un- 130

derstood as limiting myself except as required by the following claims when construed in the light of the prior art.

Having thus described the invention, what

5 I claim is:

1. The combination with a power press having a clutch, and a throw-out for said clutch, of an operating member pivoted at one end and adapted to engage said throw-out, stops for positioning said member to engage different points of said throw-out, a spring for holding said operating member against either of said stops, and means for changing the direction of pull of said spring 10 on said operating member to hold it in alternate positions, in one of which positions it will be automatically released from the throw-out by revolution of the press and in the other of said positions it will be unaffected by revolution of the press.

2. The combination with a power press having a clutch, and a throw-out for said clutch, of an operating bar pivoted at one end and adapted to engage said throw-out, an adjustably mounted member adapted to project at either side of the free end of said operating bar as desired, and a spring connection between said member and free end of the bar serving to hold the latter in one 25 position of said member so that it will engage the throw-out and be disengaged by revolution of the press, said spring connection in the other position of the member holding the connecting bar in engagement 30 with the throw-out so that it will be unaffected by revolution of the press.

3. The combination with a power press having a clutch, and a throw-out for said clutch, of an operating bar pivoted at one end and adapted to engage said throw-out at both ends of the swing of said bar, said bar being adapted in one position to be disengaged by revolution of the clutch and in the other position to be unaffected thereby, and means for resiliently holding said bar in 45 engagement with the throw-out at each of its said positions.

4. The combination with a power press having a clutch, and a throw-out for said clutch, of an operating bar pivoted at one end and adapted to engage said throw-out at both ends of the swing of said bar, said bar being adapted in one position to be disengaged by revolution of the clutch and in the other position to be unaffected thereby, a swinging arm adapted to project at either side of the free end of the operating bar, a spring connection between said arm and the free end of the bar, and means for 55 releasably holding said arm in its positions.

5. The combination with a power press having a clutch member with a clutch pin, and a throw-out for said clutch pin, of an unyielding bar for operating said throw-out pivoted at its lower end, stops for positioning

said bar so that it lies in the path of said clutch pin and alternately so that it lies out of the path of said clutch pin, and means for resiliently holding said bar swung against either of said stops.

6. The combination with a power press having a clutch member with a clutch pin, and a throw-out for said clutch pin, of an unyielding bar for operating said throw-out pivoted at its lower end, stops on the throw-out for positioning said bar in engagement therewith so that it lies in the path of said clutch pin and alternately so that it lies out of the path of said clutch pin, and means for resiliently holding said bar swung 70 against either of said stops.

7. The combination with a power press having a clutch member with a clutch pin, and a throw-out for said clutch pin having spaced stops, of an unyielding bar for operating said throw-out pivoted at its lower end and adapted to lie against either of said stops to operate the throw-out, the upper part of said bar in one of such positions being in the path of the clutch pin as it rotates and in the other position being out of said path, and means for resiliently holding said bar swung against either of said stops.

8. The combination with a power press having a clutch, and a throw-out for said clutch, of an operating bar pivoted at one end and adapted to engage said throw-out at both ends of the swing of said bar, said bar being adapted in one position to be disengaged by revolution of the clutch and in the other position to be unaffected thereby, a swinging arm adapted to project at either side of the free end of the operating bar, and a spring connection between said arm and the free end of the bar.

9. The combination with a power press having a clutch, and a throw-out for said clutch, of an operating bar pivoted at one end and adapted to engage said throw-out at both ends of the swing of said bar, said bar being adapted in one position to be disengaged by revolution of the clutch and in the other position to be unaffected thereby, a spring connection at the free end of the bar, and means for securing said spring connection to the press at either side of the bar.

10. The combination with a power press having a clutch, and a throw-out for said clutch, of an operating bar pivoted at one end and adapted to engage said throw-out at both ends of the swing of said bar, said bar being adapted in one position to be disengaged by revolution of the clutch and in the other position to be unaffected thereby, and means for resiliently connecting the free end of the bar to the press at either side of said bar.

11. The combination with a power press having a clutch, and a throw-out for said clutch mounted upon a boss providing

shoulders at its opposite sides, of a member secured to said throw-out to swing therewith and having projecting arms at opposite sides of the throw-out, and stop screws in said arms adapted to engage said shoulders.

12. The combination with a power press having a clutch, and a throw-out for said clutch mounted upon a boss providing shoul-

ders at its opposite sides, of a member secured to said throw-out concentrically with ¹⁰ opposite stop screws in said member to engage said shoulders, an arm on said member, and a spring engaging said arm to normally hold one of said stop screws in engagement with said shoulder.

EDMUND W. ZEH.
